MAGNIFYING READING BAR

Florence M. Chapman, Oakland, Calif.

Application February 10, 1958, Serial No. 49,565

Term of patent 14 years

(Cl. D57—1)

I claim:

The ornamental design for a magnifying reading bar, substantially as shown.
